UNITED STATES PATENT OFFICE.

JOHN ALONZO, OF DEBORGLIA, MONTANA.

RAILWAY-SWITCH.

1,273,984.

Specification of Letters Patent. Patented July 30, 1918.

Application filed October 31, 1917. Serial No. 199,533.

To all whom it may concern:

Be it known that I, JOHN ALONZO, a subject of the King of Italy, residing at Deborgia, in the county of Mineral and State 5 of Montana, have invented certain new and useful Improvements in Railway-Switches; and I do declare the following to be a full, clear, and exact description of the invention, such as will enable others skilled in 10 the art to which it appertains to make and use the same.

My invention relates to improvements in switches for steam railroads, electric railroads and other kinds, and its primary object is to provide a switch which will not become clogged by snow, ice, sand, mud or other foreign matter and it will eliminate 15 all gaps which cause many railroad accidents.

In carrying out the above object, the 20 switch tongues are mounted for vertical movement rather than for horizontal swinging movement, and a plurality of cams are provided for raising and lowering said tongues, a further object of the invention being to 25 provide a pair of sills upon which the cams rest, so that all strain is relieved from the rock shafts upon which the cams are mounted. While the invention is primarily intended for steam roads, it may be used in 30 electric roads at street crossings and similar places and where the switch is operated by electric power, the vertical movement of switch points will obviate dangers resulting from suddenly changing the points of the 35 switch, such for example, as a pedestrian having his foot caught between the rail and a moving switch point.

Still another object is to provide simple means whereby the accumulation of ice and 40 the like upon the aforesaid sills is entirely prevented, and whereby the movement of the cams will remove any ice which might possibly form on the portions of said sills engaged by the cams.

45 A still further object is to provide an effective rigid support for the switch, said support including two series of posts which are set in a pit, these posts being so constructed as to support the rails and at the 50 same time guide the switch tongues in their vertical movement.

An additional object is to provide novel means for tying the line and the switch rails together to prevent creeping which 55 might otherwise impair the efficiency of the

switch, and to so construct such means as to cause the same to hold the aforesaid posts in properly spaced relation, and also to prevent injury to the super-structure of the switch in case derailed wheels are caused to 60 run by the switch.

Still other objects are to provide a novel type of switch stand for turning one of the rock shafts which carry the cams, and to provide this shaft with shifting weights 65 which assist in moving it to proper position for either opening or closing the switch, after said shaft has been first turned to a predetermined degree by hand, said weights also holding the switch against displacement in case the switch lever gears should 70 unmash.

Additional objects are to provide novel means to hold the switch tongues against longitudinal shifting when their cams are 75 operated, and to provide for holding the track rails in proper gage and preventing the switch tongues from splitting.

With the foregoing general objects in view, the invention resides in the novel features of construction and unique combinations of parts to be hereinafter fully described and claimed, the descriptive matter being supplemented by the accompanying drawings which form a part of this specification and in which:

Figure 1 is a side elevation partly in section of the improved switch;

Fig. 1^a is a perspective view of the switch;

Fig. 2 is substantially a central vertical 90 longitudinal section;

Fig. 3 is a top plan view with parts removed;

Fig. 3^a is a detail top plan of the right hand portion of Fig. 1^a showing a modified 95 form of switch tongue;

Figs. 4 and 5 are horizontal sections on the planes indicated by the lines 4—4 and 5—5 of Fig. 2;

Figs. 6, 7, 8, 9, 10 and 11 are vertical transverse sections on the planes indicated respectively by the lines 6—6, 7—7, 8—8, 9—9, 10—10 and 11—11 of Fig. 2;

Fig. 12 is a perspective view of one of the switch tongues;

Fig. 13 is an enlarged side elevation of a portion of one of the sills and one of the cams resting thereon, showing more particularly the guards which prevent accumulation of ice and the like upon the sills;

Fig. 14 is a transverse section of Fig. 13 on the planes indicated by the line 14—14 thereof;

Fig. 15 is a detail transverse section on the 5 plane of the line 15—15 of Fig. 3, showing more particularly the switch stand;

Fig. 16 is a top plan view of the stand with the vertical shaft thereof in section; and

10 Fig. 17 is a vertical section on the plane indicated by the line 17—17 of Fig. 16.

In the drawings above briefly described, the numeral 1 designates the uninterrupted rail of the main track, whereas the numeral 15 2 designates the two spaced portions of the other main rail, one of said portions having a lateral branch 3 forming one rail of a siding whose other rail is designated by the numeral 4, two of the improved switch 20 tongues 5 being employed for guiding a train from the main track onto the siding, or for permitting it to continue its course along said main track. As will be herein-after fully described, the tongues 5 have a 25 truly vertical movement rather than swinging laterally in the usual manner, and although these tongues could merely abut the rails 2 and 4 as seen in Fig. 3^a, overlapped joints 6 are preferably provided in order to 30 prevent pounding of the car wheels, so that the train may run more smoothly from one track onto the other or along the main track. Another feature which will in most cases be employed, but which could well give way to 35 other suitable construction should occasion demand, are fillers 7 secured between the converging portions of the rails of the main track and siding, these fillers serving not only to impart the necessary rigidity to the 40 switch, but to assist in guiding the switch tongues 5.

For supporting the several parts so far described, holding the track rails in proper gage, and preventing the switch tongues 45 from splitting, a plurality of arches are provided, five of such arches being here shown although any preferred number could be employed. Since the construction of the several arches is slightly different, I will refer 50 to them by the letters A, B, C, D and E, and will refer to each in turn.

Arch A includes a pair of vertical posts 8 upon whose upper ends the rails 1 and 2 rest, said posts having abutments 9 bearing 55 against the outer sides of said rails as illustrated for instance in Fig. 6. Each post 8 is also provided in its inner side with a vertically extending recess 10, these recesses receiving therein the switch tongues 5, the 60 movement of these tongues being guided by one side of the recesses and by the legs 11 which depend from the crown bar or tie member 12 of the arch, said legs being suitably secured to the posts 8 by bolts or any 65 other fasteners.

Arch B (Fig. 5) includes vertical posts 8^a similar to the posts 8, the upper ends of said first named posts supporting thereon the rails 1 and 2 and having abutments 9^a which bear against the outer sides of these 70 rails. The tie member 12^a of arch B is provided with depending legs 11^a suitably secured to the posts 8^a, said tie member also having vertical lugs 13^a corresponding to the lugs 13 of the tie member 12. Whereas lugs 75 13 contact with the inner sides of the switch tongues 5, the lugs 13^a serve to prevent inward shifting of the rails 1 and 2, spacing blocks 14 being interposed between said rails and lugs as shown. In most cases, bolts 15 80 will pass through the lugs 13^a, the blocks 14, the rails 1 or 2, and the abutments 9^a, whereby all parts are rigidly secured together. It will be observed that the posts 8^a of the arch B are not provided with any vertical guideways 85 for the switch tongues 5, since these tongues do not extend entirely to said arch as is clear from several of the views.

The arch C is of substantially the same construction as the arch A. The posts 8^b 90 of this arch support the rails on their upper ends and are provided with abutments 9^b abutting the outer sides of said rails, said abutments having transverse recesses 16 and vertical key ways 17 intersecting the same, 95 the abutments of the arches A and D being also formed with such recesses and keyways as will be clear from Fig. 4. The several recesses 16 receive rigid loops 18 which extend outwardly from the rails 1 and 3, vertical keys 19 being passed through said loops and the keyways 17 to prevent inward movement of these rails.

The posts 8^b are formed with recesses 10^b 100 coacting with the legs 11^b of the tie member 12^b, in forming additional vertical guideways for the switch tongues 5, all this construction being clearly illustrated in Fig. 10.

The principal difference between the arch D and those above described, is that the legs 110 8^c thereof are formed with vertical slots 10^c which are spaced outwardly from the legs 11^c of the tie members 12^c, the construction being otherwise substantially the same. The slots 10^c receive the switch tongues 5 as indicated in Fig. 8 and coöperate with the other vertical guideways, for insuring that these tongues shall move along predetermined lines. The lugs 13^c of the tie member 12^c 115 anchor the tapered ends of the rails 4 and 2, whereas the lugs 13^b of tie member 12^b above described, assist in guiding the switch tongues 5 in the same manner as the lugs 13 of arch A.

The arch E is very similar to arch B, the 125 posts 8^d of this arch supporting both the line and siding rails as shown for instance in Fig. 9, said posts being provided with abutments 9^d but having no vertical guideways for the tongues 5, since these tongues terminate short 130

of the posts. The tie member 12^a of arch E is provided with legs 11^a bolted or otherwise secured to the posts 8^a, and the lugs 13^d of said tie members assist in anchoring the adjacent portions of the rails 1, 4, 2 and 3, bolts 20 being passed through these parts as well as through the spacers 7 and spacing blocks 14^d which are interposed between said lugs and the adjacent rails (see Figs. 3, 4 10 and 9).

The lower ends of the posts of the several arches A, B, C, D and E, are provided with suitable feet 21 which are spiked to cross-ties 22 positioned in the bottom of a suitable pit 23, said feet preferably having anti-slipping ribs 24 as shown most clearly in the several transverse sections. The pit 23 may be walled up in any preferred manner to prevent the sides and ends from caving in, and 15 the bottom of this pit will preferably be provided with ballast such as commonly employed upon railways, this ballast serving to anchor the ties 22 and permit raising and lowering of such ties as occasion may demand.

Adjacent their abutments, the vertical posts of certain of the arches are provided with laterally extending ledges 25, said ledges and the tie members 12, 12^a, 12^b, 12^c, 30 and 12^d, serving to support longitudinal tie plates 26 whose ends are reduced in width and secured at 27 to the rails, at opposite ends of the switch, so that creeping of these rails in such a manner as to possibly impair 35 the proper operation of the switch, will be prevented. The plates 26 are formed with suitable notches 28 through which the abutments 9, 9^a, 9^b, 9^c and 9^d and the lugs 13, 13^a, 13^b, 13^c and 13^d rise, said plates being secured 40 to the tie members 12, 12^a, 12^b, 12^c and 12^d, so that possible relative shifting of the several arches is prevented. The tie plates 26 also serve to receive the wheels of a derailed car in case the latter should approach the 45 switch, and said plates are provided with flanges 29 along their edges so that the car wheels are retained thereon and prevented from injuring the substructure of the switch and the operating means of the switch 50 tongues 5. The ends of the outermost plates 26 are preferably beveled or inclined as shown at 30 in Figs. 1 and 3, so as to form no obstruction to prevent a car wheel from passing thereon.

Extending longitudinally beneath the switch tongues 5, are two sills 40, these sills being secured in the lower ends of the several recesses 10, 10^a, 10^b, and 10^c, the ends of said sills, however, being secured to suitable 60 flanges or the like 41 on the end-most arches B and E. Resting on the sills 40 at suitably spaced intervals, are cams 42 upon which the switch tongues 5 rest, the cams of one tongue being lowered when the others are 65 raised. A plurality of transverse shafts 43

carry the cams 42 and at their ends are suitably mounted in bearings 44 secured to the sills 40, said bearings preferably having passages 45 which will drain any water therefrom and thus prevent the formation of ice 70 which might otherwise prevent proper turning of the shafts.

The upper edges of the sills 40 are flat as indicated at 46, where engaged by the cams 42 when the latter are in raised or in operative position, but the remainder of these edges are sharpened as indicated at 47 to prevent the accumulation of ice thereon, it being intended that any water shall drip from these edges before freezing thereon. 75 As a safe guard against the accumulation of ice upon the flat portions 46, guards 48 are hinged at 49 to the cams 42, said guards having downwardly turned outer ends which slide along the sills when the cams are moved from one position to the other. When the cams 42 lie flat upon the sills as shown in Fig. 1, guards 48 overlie the portions of the sill upon which said cams rest when they are moved into operative position. By the 80 provision of these guards, therefore, there is no possibility whatever of snow or ice accumulating on the flat portions 46 and preventing the cams 42 from rising to operative position. In case any thin film of ice should 85 form on the sills 40 while the cams are raised, lowering of these cams will chip the ice from the adjacent portions of the sills, due to the knife edges 47, and thus the movement of the cams to an inoperative position 90 will not be impaired.

Particular emphasis is laid upon the fact that the several cams 42 are supported upon the sills 40 and not upon the shafts 43, the latter serving merely as operating means for 105 said cams. By the provision of these sills, therefore, all strain which would otherwise be placed on the rock shafts is prevented, this being a highly important feature of my invention. All of the rock shafts are connected for simultaneous movement by a longitudinal link 50 to which crank arms 51 of the shafts are pivoted, one of said shafts, preferably the one at the center of the series, being extended laterally in a suitable trough 110 or housing 51 and connected at 52 to a shaft 53 which may be turned by beveled gears 54 from a vertical shaft 55 which is rotatably mounted in a suitable switch stand 56. The upper end of the shaft 55 carries a suitable lateral arm 57 to which a hand lever 58 is pivoted for movement toward and away from the shaft. When swung toward the shaft, the lever 58 is receivable in either one of a pair of notches 59 in a plate 60 which 115 is held against movement, whereby after the shaft 55 has been turned to throw the entire switch to one position or the other, the lever 58 may be swung downwardly into the proper notch 59 so that the switch may be 120 125 130

locked. A pad lock 61 may be provided for holding the lever 58 against movement to an unlocked position by unauthorized parties.

In order that the switch operating means may be so adjusted as to permit the tongues 5 to be raised to an exact level with the rails, it is often necessary to slightly vary the throw of the lever 58, and in order that this may be done, it is necessary to mount the plate 60 adjustably, so that the lever may properly engage the notches 59. As the preferred means of so adjusting plates 60, this plate is shown supported upon a flat circular head 62 with which the stand 56 is provided, bolts 63 being passed through said head and plate, either one or the other having slots 64 through which said bolts extend, so that when these bolts are loosened, the plate 60 may be turned to the required extent. To assist in throwing the switch, and to prevent displacement of the switch in case its operating gears should break or unmesh, inclined arms 65 extend in opposite directions from the rock shaft 43 which is connected to shaft 53, weights 66 being slidable along said arms between the shafts and stops 67 on the outer ends of the arms. After the shafts 43 have been turned to a predetermined amount by hand, the weights 66 will slide along the arms 65 by gravity, one weight moving to the outer end of its arm while the other travels to the inner end of the other arm. The weight 66 at the outer end of the arm now tends to assist the operation, due to the action of gravity. It is to be noted that the primary function for the sliding weights 66 is to hold the switch points in their set positions and prevent them from being moved by vibration which might occur should the switch operating lever become unlocked.

I have stated that the several cams 42 are so arranged as to raise one tongue 5 when the other is lowered, and since the force of gravity might not be sufficient in some cases to quickly lower the one tongue while the other is being raised, links 68 (Fig. 2) are preferably pivoted to certain of said cams at one end, whereas the other ends of said links are formed with loops 69 which register with slots 70 in the tongues 5, pins or bolts 71 being passed through said loops and slots as shown. By this arrangement, lowering of the cams will positively lower the tongues so that the possibility of either tongue remaining in a raised position when it should be lowered, is prevented.

In most cases a removable cover 75 will be used between the inner tie plates 26 to exclude snow, sand, and the like. It is important to prevent water and dust from entering the pit, but it is to be observed that the posts 8, 8^a, 8^b, 8^c and 8^d all extend an appreciable distance below the switch op-

erating means and thus a large quantity of such foreign matter may collect in the pit without interfering with the operation of the switch. In short, I have provided a switch which cannot be blocked from the usual causes and it is not therefore necessary to employ laborers for the express purpose of keeping the switches open as is now done. Whenever advisable, however, the cover 75 may be removed so that accumulated sand, dust, ice and the like may be removed.

Another feature shown, is the provision of one or more links 5^a for preventing longitudinal shifting of the tongues 5 when their cams are operated. It is thus insured that binding of these tongues shall not occur.

In operation, the hand lever 58 is released and swung outwardly from the notch 59 in which it has been secured, movement of this lever in the proper direction now serving to turn shaft 55 which in turn rotates shaft 53, the latter now serving to rock the series of shafts 43 so that one series of cams 42 is raised and the other lowered. This simultaneously raises one switch tongue and lowers the other so that the train will be directed either onto the siding or along the main track. During this operation, the weights 66 and arms 65 assist in the manner above set forth and the guards 48 are moved along the sills 40, these guards preventing accumulations of dust and ice upon the sills when the cams are lowered, which might otherwise interfere with proper raising of said cams.

From the foregoing, taken in connection with the accompanying drawings, it will be obvious that although I have provided a comparatively simple and inexpensive switch, it will be highly efficient and durable. Since probably the best results are obtained from the features of construction shown and described, these features are preferably employed, but I wish it understood that within the scope of the invention as claimed, numerous minor changes may well be made. I also intend that the term "tongue" in the appended claims shall be given a sufficiently broad interpretation to include the "bridging blocks" of my co-pending application Serial No. 199,532, filed on even date therewith.

I claim:

1. In combination with a railway, a rail tongue movable vertically, vertical supports below the rails, a sill secured to said supports and extending longitudinally beneath said tongue, a cam resting rockably on said sill and supporting said tongue, and means for rocking said cam to operate said tongue.

2. In a railway switch, the combination of two parallel series of posts whose upper ends support the rails, said posts having vertical guideways, a pair of vertically movable switch tongues mounted in said guideways,

means for raising and lowering said tongues, and tie members extending between the two series of posts.

3. In a railway switch, the combination of 5 two parallel series of posts whose upper ends support the rails, said posts having vertical guideways, a pair of vertically movable switch tongues mounted in said guideways, a pair of longitudinal sills received in the 10 lower ends of said guideways and secured rigidly to said posts, cams mounted on said sills and supporting said tongues, means for actuating said cams to operate said tongues, and tie members extending between said 15 posts.

4. In a railway switch, the combination of two series of posts whose upper ends support the rails, the inner sides of said posts having vertical recesses, a pair of vertically 20 movable switch tongues received slidably in said recesses, cams for supporting said tongues and means for operating said cams, a pair of sills extending longitudinally beneath said tongues and positioned in the 25 bottoms of said recesses, said sills supporting said cams, and arched tie members between said series of posts, the legs of said members being secured to said posts and closing the inner sides of said recesses to 30 guide the tongues in the latter.

5. In combination, a rail tongue movable vertically, a rigidly supported sill extending longitudinally beneath said tongue, a cam supporting said tongue and resting on said 35 sill when in operative position, and a guard on said cam overlying a portion of the sill when said cam is in inoperative position to prevent accumulation of any foreign matter on the portion of said sill upon which said 40 cam rests when operative.

6. A structure as specified in claim 5, said guard being pivoted to said cam and having a downwardly turned outer end which slides along said sill when said cam is shifted from 45 one position to the other.

7. In combination, a rail tongue movable vertically, a rocking cam for actuating said tongue, means for turning said cam to operative and inoperative positions, and a sill 50 upon which said cam rests in either position, the portion of the sill which supports the cam when inoperative, having its upper edge sharpened.

8. A structure as specified in claim 7, together with a guard carried by said cam to overlie the sill when said cam is in inoperative position to prevent accumulation of foreign matter on the portion of said sill which supports said cam when operative.

60 9. In a railway switch the combination of two series of posts whose upper ends support the line and switch rails, switch tongues coacting with said rails, longitudinal tie plates on opposite sides of said rails over the 65 base flanges thereof and extending to points

beyond said tongues, means for securing the ends of said tie plates to the vertical webs of said rails and means for securing said plates to the upper ends of said posts.

10. In a railway switch, the combination 70 of two series of posts whose upper ends support the rails, said posts having vertical guideways, a pair of vertically movable switch tongues received in said guideways, means for raising and lowering said tongues, 75 tie members extending between said posts near their upper ends, ledges formed on the outer side of certain of said posts near their upper ends, and longitudinal tie plates extending along the outer and inner sides of the rails, said plates being secured to said tie members and ledges and having openings in which the upper ends of the posts are received.

11. In a railway switch, the combination 85 of switch tongues, means for operating said tongues including a horizontal rock shaft and means for turning it, oppositely extending inclined arms on said shaft, and weights slidable freely along said arms. 90

12. In a railway switch, the combination of switch tongues, means for operating said tongues including a horizontal rock shaft and means for turning it, inclined arms carried by said shaft and extending in opposite 95 directions, stops on the outer ends of said arms, and weights slidable freely on said arms between said shaft and said stops.

13. In combination, a vertically movable tongue, a rocking cam for raising said tongue, means for rocking said cam, and a flexible connection between said cam and said tongue for pulling the latter downwardly when said cam is lowered. 100

14. A structure as specified in claim 13, 105 said connection comprising a link pivoted to said cam and having a loop, said tongue having a slot with which said loop registers, and a pin passing loosely through said loop and slot. 110

15. In a railway switch, the combination of 115 a pair of vertically movable switch tongues, sills extending longitudinally beneath said tongues, cams upon which said tongues rest, transverse rock shafts upon which said cams are mounted, bearings for said shafts secured to said sills and means for rocking said shafts simultaneously.

16. In a railway switch, the combination 120 of a pair of vertically movable switch tongues, sills extending longitudinally beneath said tongues, cams upon which said tongues rest, transverse rock shafts upon which said cams are mounted, bearings for said shafts secured to said sills, means for rocking one shaft by hand, means for transmitting motion from said one shaft to the others, inclined arms extending in opposite directions from said one shaft and weights 125 slidable freely along said arms. 130

17. In a railway switch, the combination of a line rail, a switch tongue movable vertically and contacting with one side of said rail, fixed abutments against which the other side of said rail bears, said abutments having recesses and keyways intersecting them, rigid loops secured to said rail and extending into said recesses, and keys in said keyways passing through said loops to hold the rail tightly against the abutments.

18. In a railway switch, the combination of a line rail, a switch tongue movable vertically and contacting with one side of said rail, fixed abutments against which the other side of said rail bears, rigid loops extending outwardly from said rail, and keys driven through said loops and engaging said abutments to hold the rail in tight contact with said abutments.

19. In a railway switch, the combination of a pair of vertically movable switch tongues, means for raising and lowering said tongues, and a plurality of vertical tie supported posts beneath the rails for supporting the latter and said raising and lowering means, said posts being adapted to be positioned in a pit and extending below said raising and lowering means, whereby foreign matter may accumulate in the bottom of said pit without obstructing the operation of the switch.

20. In a railway switch, the combination of two series of posts whose upper ends support the rails, the inner sides of said posts

having vertical recesses, a pair of vertically movable switch tongues received slidably in said recesses, means for moving said tongues vertically, and arched tie members between said series of posts, the legs of said tie members being secured to said posts and closing the inner sides of said recesses to guide said tongues in the latter.

21. Switch operating means comprising a vertical rock shaft, a hand lever pivoted to said shaft for movement toward and away therefrom, a stand in which said shaft is mounted, said stand having a flat head on its upper end, a flat plate resting on said head and having an opening through which said shaft passes, the edge of said plate having notches in which said lever is receivable when the switch is respectively opened and closed, and means for securing said plate to said head and permitting adjustment of the former around said shaft.

22. The combination with a railway having vertically movable longitudinal tongues, and cams mounted on transverse axes for raising said tongues; of links pivoted at one end to said tongues and pivoted at their other ends to fixed means.

In testimony whereof I have hereunto set my hand in the presence of a subscribing witness.

JOHN ALONZO.

Witness:

W. R. BAUM.
